FIGURE 1 is a perspective view of a salad cup or similar article, showing my new design,

The essential feature of my design resides in the combination of the particular peripheral lip configuration with a salad cup of the particular configuration and proportions shown.

I claim:

The ornamental design for a salad cup, as shown and described.
